UNITED STATES PATENT OFFICE

CLARENCE D. TRUSSELL, OF NEW YORK, N. Y., ASSIGNOR TO TRUSSELL MANUFACTURING COMPANY, OF NEW YORK, N. Y., A CORPORATION OF NEW YORK

TEMPORARY BINDER.

1,104,394.

Specification of Letters Patent. Patented July 21, 1914.

Application filed December 26, 1903. Serial No. 469,226.

To all whom it may concern:

Be it known that I, CLARENCE D. TRUSSELL, a citizen of the United States, residing in the borough of Manhattan, New York city, in the county of New York and State of New York, have invented certain new and useful Improvements in Temporary Binders, of which the following is a specification.

My invention relates to temporary binders for blank books, account and memorandum books, and the like, in which the leaves may be inserted or removed at will.

The object of my invention is to provide a temporary binder with simple and neat operating parts, which may be manufactured at slight cost. My method of making the covers of the binders and securing the same to the operating metallic parts obviates the use of paste or stitches. The covers of my binder will lie snugly along the operating parts and sheets to reduce the bulk of the binder when carried in the pocket. My covers will not buckle or become distorted as is usual with covers of several layers pasted together, and, although a hinged portion is provided for the covers, they are so strengthened at the ends of said hinged portions that they are not liable to be worn or torn away.

Figure 1 of the drawings is a perspective view of the temporary binder, the sheets not being in place. Fig. 2 is a sectional view on the line 2--2 of Fig. 1, the sheets being in place. Fig. 3 is a view similar to Fig. 2, the sheet-holding prongs being shown in open position. Fig. 4 is a similar sectional view, the covers and sheet-holding prongs both being shown in closed position. Fig. 5 is a plan view of the metallic plates extending through the binder with their integral prongs. Fig. 6 is a bottom view of the spring plate. Fig. 7 is a plan view of the binding plate. Fig. 8 is a plan view of the base plate.

Referring to the drawings, 1 is the base plate, preferably made of tin or other substantially non-resilient metal, having the end notches 2 and side wings or flanges 3 notched as indicated at 4. The binding plate 5 has end projections 6 adapted to engage notches 2 in the base plate, piercing the back 7 from which extend on either side the covers 8, which are channeled or grooved lengthwise at 9, such channels or grooves 9 extending not quite to the edges of the covers, so that ridges 10 are left at the edges of

equal thickness with the covers. The binding plate is covered by a thin leather envelop 11. The two plates 12 are identical in size and shape, the integral curved sheet holding prongs 13 extending therefrom. The plates 12 are provided with oppositely arranged notches 14 adapted to be engaged by the blocks 15 which have on one side a deep groove 16 tightly fitting one of the plates 12, while the opposite groove, 17, is shallow and is engaged by the notch 14 in the opposite plate 12. The spring plate 18 has downwardly curved wings or flanges 19 notched as indicated at 20. The sheets or leaves are designated by the number 21.

The plates 12 are adapted to be punched from sheet metal (Fig. 5 showing the blanks before the prongs 13 are bent to shape), both plates being the same in configuration. After being punched from the sheet the integral prongs 13 are bent upward and curved inward as indicated in Figs. 1, 2, 3 and 4. The deep grooves 16 in blocks 15 tightly engage one of the plates 12 at notches 14, while the shallow grooves 17 of blocks 15 are so engaged by the opposite notches 14 in the opposite plate 12 as to form a loose joint. When the parts are assembled, the outer edges of plates 12 are engaged by the non-resilient base plate 1 whose side wings or flanges 3 have the notches 4 for the reception of the upturned prongs 13. The resilient spring plate 18 is then forced over the parts to retain the same in position, the prongs 13 passing through the notches 20. When the prongs are in closed position as indicated in Figs. 1, 2 and 4, the spring plate 18 holds them together. To open the prongs, they are pulled apart by the fingers or other operating means (not shown). The plates 12 being integral with the prongs 13, will be shifted upward into the position indicated in Fig. 3, the shallow groove 17 in blocks 15 serving by its engagement with notches 14 as a joint. The spring plate 18 acts as a stop to limit the opening movement of the prongs, as best illustrated in Fig. 3. The prongs 13 are retained open by the resiliency of spring plate 18 until they are forced together and closed by the fingers. Thus, the resiliency of spring plate 18 retains the prongs together when closed in the position indicated in Fig. 2 and also retains them open when they are in the position indicated in Fig. 3. The back 7 and covers 8 are made

in one integral piece, preferably leather, a construction materially saving cost and presenting a neat appearance. I have found pigskin the best material for the back and covers. The use of paste for securing together several layers of the covers is dispensed with and this obviates the objectionable feature of buckling or bending caused by the drying of the paste or differences in shrinkage of the layers under varying conditions of temperature and moisture. The channels or grooves 9 adjacent to and parallel with the operating parts weaken the material of the covers so as to form a sort of hinge. By removing the material to form the channels or grooves 9 the covers are permitted to close neatly and snugly as best indicated in Fig. 4. The channels or grooves 9 terminate just before reaching the edges of the covers so that the points 10 present a smooth appearance outside and strengthen the covers at the extremities of the hinged portions, so that they will not be torn in use.

The metallic binding plate 5 is covered by a thin envelop of leather or similar material, so that metallic parts will not be exposed at the outside of the binder.

What I claim as new and desire to secure by Letters Patent is:

1. A temporary binder including in combination a back and covers composed of a single-ply integral piece of flexible material, a loose-leaf binding mechanism, and means passing through said back and fastening said mechanism permanently upon the inner face thereof.

2. A temporary binder including in combination a back and covers composed of a single-ply integral piece of leather so that the cut edges of said piece of leather constitute the edges of the covers and back, a loose-leaf binding mechanism, and means passing through said back and fastening said mechanism permanently upon the inner face thereof.

3. A temporary binder including in combination a back and covers composed of a single-ply integral piece of flexible material, a loose-leaf binding mechanism on the inner side of said back, a binding plate on the outer side of said back and means for clamping said back between said mechanism and said plate.

4. A temporary binder including in combination a back and covers composed of a single-ply integral piece of flexible material, a loose-leaf binding mechanism on the in-

ner side of said back and a binding plate on the outer side of said back having ears passing through said back and engaging a part of said mechanism so as to fasten the latter to said back.

5. A temporary binder including in combination a back and covers composed of a single-ply integral piece of flexible material, and a loose-leaf binding mechanism permanently attached thereto, said integral piece of flexible material being of reduced strength along two lines substantially parallel with and at opposite sides of the back, so as to provide definite lines for the bending or hinging of the flexible covers relatively to the back.

6. In a temporary binder, a one-piece flexible member constituting the back and covers, provided with a weakened portion extending lengthwise on each side of the operating parts, said weakened portion terminating before the edges of the covers are reached, and means to secure the back and covers to the operating parts.

7. In a temporary binder, a base-plate, two prong-carrying plates having their outer longitudinal edges held by said base plate, the prongs being integral with said carrying plates, a plurality of joint blocks 15 each having grooves along its opposite edges engaging the adjacent inner edges of said carrying plates, said carrying plates having notches engaging said blocks, and an upper spring plate acting on said carrying plates to hold them yieldingly in the positions corresponding to the open and the closed positions of the prongs.

8. In a temporary binder, a pair of prong-carrying plates, means for pressing them toward each other and joint blocks 15 between their inner edges, said joint blocks being tightly engaged with one of said plates and loosely engaged with the other.

9. In a temporary binder, a base plate, a pair of prong-carrying plates held at their outer longitudinal edges by said base plate and an upper spring plate acting on said carrying plates to hold them yieldingly in the positions corresponding to the open and the closed positions of the prongs.

Signed at New York city in the county of New York and State of New York this 23rd day of December A. D., 1908.

CLARENCE D. TRUSSELL.
